UNITED STATES PATENT OFFICE.

HORACE WYMAN, OF WORCESTER, MASSACHUSETTS, ASSIGNOR TO THE CROMPTON & KNOWLES LOOM WORKS, OF SAME PLACE.

LOOM.

SPECIFICATION forming part of Letters Patent No. 643,389, dated February 13, 1900.

Application filed November 20, 1899. Serial No. 737,606. (No model.)

To all whom it may concern:

Be it known that I, HORACE WYMAN, a citizen of the United States, residing at Worcester, in the county of Worcester and State of Massachusetts, have invented certain new and useful Improvements in Looms, of which the following is a specification.

My invention relates to looms, and more particularly to a signal attachment for shuttle-changing looms of the class shown and described in Patent No. 614,369, of November 15, 1898. In said class of looms it becomes necessary for the attendant to visit the loom and place a shuttle with fresh filling on the spare-shuttle holder after the transfer of the spare shuttle to the lay. The spare-shuttle holder is held normally inoperative near that end of the lay in which the transfer is made. In order to enable the attendant to immediately know of the transfer of the spare shuttle, I provide a signal to be brought prominently into view whenever the spare-shuttle holder is operated to transfer the spare shuttle to the lay.

My signal attachment preferably consists of a pivoted signal-arm upon a stand fixed to the loom-frame and near the spare-shuttle holder when it is in its inoperative position. When the spare-shuttle holder moves to transfer the spare shuttle, the signal-arm is also moved to bring the signal into a more prominent position to be seen by the attendant, who may be at another loom. The display of the signal will notify the attendant that it is necessary to visit the loom to supply another spare shuttle.

My invention consists in certain novel features of construction of my signal attachment, in combination with the spare-shuttle holder, as will be hereinafter fully described.

Referring to the drawings, Figure 1 is a plan view of a detached portion of one end of the stationary bracket at one end of a loom and the movable spare-shuttle holder-plate of the shuttle-feeder mechanism with a spare shuttle thereon and my signal attachment combined therewith. Fig. 2 is a front view of the parts shown in Fig. 1 looking in the direction of arrow *a*, same figure. Fig. 3 corresponds to Fig. 2, but shows the spare-shuttle holder-plate of the shuttle-feeder mechanism

in its raised position without a spare shuttle thereon (the shuttle having been transferred to the lay) and the signal in its displayed position; and Fig. 4 is a vertical cross-section on line 1 1, Fig. 1, looking in the direction of arrow *b*, same figure. The shuttle is shown in broken lines.

In the accompanying drawings, 1 is the upper portion of the frame at one side of the loom. 2 is the end of the breast-beam. 3 is a stand secured to the frame or loom side. 4 is the spare-shuttle holder-plate of the shuttle-feeder mechanism, bolted to the upper end of the lever or bar 5, pivoted at its lower end 6 (not shown) in the usual way and as fully shown and described in said Patent No. 614,369. Upon the plate 4 rests the spare shuttle 6, as shown in Figs. 1 and 2.

All of the above parts may be of the ordinary and well-known construction and operation and are fully shown and described in said Patent No. 614,369.

I will now describe my signal attachment combined with the parts shown in the drawings and above described.

An arm 7 has in this instance a weight 8 thereon at one end and is pivotally mounted on a stud or pin 9, secured to the stand 3. The opposite or free end of the arm 7 carries 80 the signal, which in this instance is a flat plate or disk 10, secured to the arm 7 by a screw 11. The signal-arm 7 is pivoted to move in a vertical plane and from the horizontal position shown in Fig. 2 to the raised position shown 85 in Fig. 3, and the weight 8 is so arranged relatively to the pivoted end of the arm 7 that it will act to hold the arm in its lowered horizontal position when moved downwardly and also in its elevated position when the projection 7' on the arm 7 is engaged by the upper rear edge 5' of the lever or arm 5 (see Fig. 3) and raised by the upper and forward movement of the spare-shuttle holder-plate 4 to transfer a spare shuttle to the lay.

The advantages of my improvements will be readily appreciated by those skilled in the art.

The attendant in tending several looms is often at a distance from some of the looms and cannot see whether or not there is a spare shuttle on the spare-shuttle holder-plate of the shuttle-feed mechanism of the loom, but

she can readily see when my signal is displayed and will thus be immediately informed when a spare shuttle must be supplied to the spare-shuttle holder-plate.

5 It will be understood that the details of construction of some of the parts of my mechanism may be varied, if desired.

Having thus described my invention, what I claim as new, and desire to secure by Letters 10 Patent, is—

In a loom of the class described, the combination with the spare-shuttle holder-plate, of a pivoted signal-arm normally held in its lowered position, and provided with a weight or its equivalent to hold it in its raised position, 15 substantially as shown and described.

HORACE WYMAN.
